(57) **CLAIM**

The ornamental design for a carving station, as shown and described.

DESCRIPTION

FIG. 1 is a perspective view of a first embodiment of the carving station;

FIG. 2 is a rear elevation view thereof;

FIG. 3 is a front elevation view thereof;

FIG. 4 is a top plan view thereof;

FIG. 5 is a bottom plan view thereof;

FIG. 6 is a right side elevation view thereof; and

FIG. 7 is a left side elevation view thereof.

FIG. 8 is a perspective view of a second embodiment of the carving station;

FIG. 9 is a rear elevation view thereof;

FIG. 10 is a front elevation view thereof;

FIG. 11 is a top plan view thereof;

FIG. 12 is a bottom plan view thereof;

FIG. 13 is a right side elevation view thereof; and

FIG. 14 is a left side elevation view thereof.

FIG. 15 is a perspective view of a third embodiment of the carving station;

FIG. 16 is a rear elevation view thereof;

FIG. 17 is a front elevation view thereof;

FIG. 18 is a top plan view thereof;

FIG. 19 is a bottom plan view thereof;

FIG. 20 is a right side elevation view thereof; and

FIG. 21 is a left side elevation view thereof.

FIG. 22 is a perspective view of a fourth embodiment of the carving station;

FIG. 23 is a rear elevation view thereof;

FIG. 24 is a front elevation view thereof;
FIG. 25 is a top plan view thereof;
FIG. 26 is a bottom plan view thereof;
FIG. 27 is a right side elevation view thereof; and
FIG. 28 is a left side elevation view thereof.
FIG. 29 is a perspective view of a fifth embodiment of the
carving station;
FIG. 30 is a rear elevation view thereof;
FIG. 31 is a front elevation view thereof;
FIG. 32 is a top plan view thereof;
FIG. 33 is a bottom plan view thereof;
FIG. 34 is a right side elevation view thereof; and

FIG. 35 is a left side elevation view thereof.
FIG. 36 is a perspective view of a sixth embodiment of the
carving station;
FIG. 37 is a rear elevation view thereof;
FIG. 38 is a front elevation view thereof;
FIG. 39 is a top plan view thereof;
FIG. 40 is a bottom plan view thereof;
FIG. 41 is a right side elevation view thereof; and,
FIG. 42 is a left side elevation view thereof.
The broken lines shown in the drawings are for illustrative
purposes only and form no part of the claimed design.
